ATTORNEY

UNITED STATES PATENT OFFICE.

CHARLES BOSWORTH, OF BROOKLYN, NEW YORK.

DESIGN FOR A PICTURE-FRAME MOLDING.

SPECIFICATION forming part of Design No. 25,218, dated March 3, 1896.

Application filed February 1, 1896. Serial No. 577,751. Term of patent 31 years.

To all whom it may concern:

- Be it known that I, CHARLES BOSWORTH, a citizen of the United States, and a resident of Brooklyn, in the county of Kings and State of New York, have invented and produced a new and original Design for Picture-Frame Moldings and the Like, of which the following is a specification, reference being had to the accompanying drawing, forming part thereof.
- 5 The essential features of my design consist in the configuration of the frame and the surface ornamentalations thereon in relief, arranged substantially as shown in the accompanying drawing.
- 10 My design is suitable for picture and other frames.
- 15 The outer surface of the molding A is composed of large curved leaves and parts of leaves forming the shell-like or leafy ornament B and the conventionally-represented leaves C, all in relief, with the foliated figure c between them, substantially as shown, all running along and parallel with the sides of the frame or molding. The exterior ornament 20 is composed of a line of foliated figures b running along the outer edge of the frame or molding. The corner is formed of conventionally-concave leaves which represent a bunch of radiating leaves D, at the base of which is placed the foliated or shell-like ornament d, as shown in the drawing.
- 25 It will be seen by reference to the corner of the frame that the protrusion of the ornamental leaves D over the concave portion is greater in extent than at any other point, so as to give effect to the corner of the design and make it still more ornamental at that point.
- The outer surface of the molding, as at E, is ogee-shaped, with the line of scroll-like figures e placed thereon, as shown in the drawing.
- 30
- 35
- 40
- 45
- What I claim is—
- The design for a molding for picture-frames, and the like, substantially as herein shown and described.
- Signed at the city of Brooklyn, county of Kings, and State of New York, this 24th day of January, 1896.
- CHARLES BOSWORTH.
